Patented Nov. 23, 1976

242,403

DISPLAY STAND FOR JEWELRY AND THE LIKE

Donna Jean Webster, 1713 Oahu Place,
Costa Mesa, Calif. 92626

Filed Nov. 3, 1975, Ser. No. 628,346

Term of patent 14 years

Int. Cl. D6—04; D20—02
U.S. Cl. D6—24

FIG. 1 is a perspective view of my new design for a display stand for jewelry and the like;

FIG. 2 is a top plan view of the present invention;

FIG. 3 is a cross-sectional view taken substantially along line 3—3 of FIG. 1;

FIG. 4 is a cross-sectional view taken substantially along line 4—4 of FIG. 1; and

FIG. 5 is a bottom plan view thereof.

I claim:

The ornamental design for display stand for jewelry and the like, as shown and described.
